UNITED STATES PATENT OFFICE.

WILLIAM R. PARK, OF TAUNTON, AND BELVIN T. WILLISTON, OF SOMERVILLE, MASSACHUSETTS.

DESIGN FOR A NOZZLE.

SPECIFICATION forming part of Design No. 26,028, dated September 15, 1896.

Application filed July 28, 1896. Serial No. 600,854. Term of patent 14 years.

To all whom it may concern:

Be it known that we, WILLIAM R. PARK, residing in Taunton, in the county of Bristol, and BELVIN T. WILLISTON, residing in Somerville, in the county of Middlesex, State of Massachusetts, have invented a Design for Nozzles, of which the following description, in connection with the accompanying drawing, is a specification, like letters on the drawing representing like parts.

The design relates to a nozzle for garden-hose; and it consists in a nozzle distinguished by its peculiar shape, which will be herein-after set forth and claimed.

The drawing shows in elevation a hose-nozzle embodying this design.

The leading feature of our design consists in the enlarged cylindrical head a on the vertical limb or portion of a bent or curved pipe-section a' , having at the end of its horizontally-disposed limb or portion a cylindrical enlargement a^2 . The cylindrical head a has arranged

about it a plurality of annular flanges b , separated from each other and disposed in substantially horizontal planes. From the lower portion or underside of the bend in the curved pipe-section a' is extended a substantially vertical projection or lug b^2 , and extending above the cylindrical head a is a cap having a substantially flat top or upper surface c and tapering or conical sides c' , extended down into the cylindrical head a .

We claim—

The design for a hose-nozzle herein shown and described.

In testimony whereof we have signed our names to this specification in the presence of two subscribing witnesses.

WILLIAM R. PARK,
BELVIN T. WILLISTON.

Witnesses:

WILLIAM A. SARGENT,
WALTER BATES FARR.
